UNITED STATES PATENT OFFICE.

JESÚS M. LÓPEZ, OF SAN ANTONIO, TEXAS.

DISTRIBUTOR.

Application filed July 28, 1921. Serial No. 488,084.

To all whom it may concern:

Be it known that I, JESÚS M. LÓPEZ, a citizen of Mexico, residing at San Antonio, in the county of Bexar and State of Texas, have invented a new and useful Distributor, of which the following is a specification.

This invention relates to flexible, eccentric, ball bearing distributors of that type used in certain classes of automobiles and is 10 designed more especially as an improvement upon the structure disclosed in a patent issued to me on March 22nd, 1921, Number 1,372,177.

One of the objects of the invention is to 15 provide improved means for holding the parts assembled.

Another object is to provide the shell with a contact surface of reduced area whereby a better contact with the roller is insured 20 and the danger of interference by accumulations of dirt, etc., is reduced to the minimum.

With the foregoing and other objects in view which will appear as the description proceeds, the invention consists of certain 25 novel details of construction and combinations of parts which will be hereinafter more fully described and pointed out in the claims, it being understood that various changes may be made in the construction 30 and arrangement of the parts without departing from the spirit or sacrificing any of the advantages of the invention as set forth in the claims.

In the accompanying drawings the preferred form of the invention has been shown.

In said drawings

Figure 1 is a rear elevation of the distributor, its shaft being shown in section.

Figure 2 is a section on line 2—2, Figure 40.

Figure 3 is a section on line 3—3, Figure 1.

Referring to the figures by characters of reference, 1 designates the shell of the distributor in which is arranged an annular track 2 the sides of which are beveled, as shown in Figure 3, so as to present a wear surface of greatly reduced area. This surface is intersected, at intervals, by contacts 50 3, such as usually employed.

Mounted on the shaft 4, so as to rotate therewith, is a sleeve 5 having a radial ear 6. This sleeve is surrounded by an inner ring 7 having a ball race 8 and a lateral 55 groove extends from the race at one point, as shown at 9 in Figure 2, so that balls can

be rolled or inserted laterally through the groove and into the race 8. The outer end of the recess or groove 9 is covered by one of a pair of wings 10 which extend inwardly 60 from the ring and are pivotally connected to the ear 6, as indicated at 11. These wings are attached to the sides of an arcuate strip 12 seated against the inner surface of the ring 7 and the outer edge portions of the 65 wings are turned toward each other so as to lap the outer face of the ring and lie close to the ball race. These inturned edge portions have been shown at 13. One of the inturned portions 13 is pressed into the 70 groove or recess 9 to hold the parts from relative movement. See the depression at 14 in Figure 2.

The free end of the strip 12 has side ears 15 which straddle the ring 7 to hold the 75 strip against lateral displacement. A projection is struck from this end portion of the strip and is engaged by one end of a spring 15', as shown at 16. The other end of the spring engages a lug 17 on the 80 sleeve 5.

A series of balls 18 is seated in the race 8 and also projects into a race 19 in the inner surface of an outer ring 20 which travels along the track 2 and contacts 3 in the 85 shell 1.

It will be noted that with the construction described the parts can be assembled readily and will not become accidentally separated. The reduced wear surface of the track 2 90 allows a better contact between the working parts because there is less danger of dirt, etc., accumulating upon the track.

If desired a supplemental spring 21 can 95 be arranged within the spring 15'.

Guide ears 22 can be extended from the sleeve 5 to lap the sides of the ring 7.

What is claimed is:

1. The combination with a shell having an interior track provided with spaced contacts, the sides of the track being beveled to provide a reduced wear surface, of a shaft engaging sleeve, inner and outer rings having races, balls within the races, one of said races having a laterally extending groove 100 opening thereto, an arcuate strip within the inner ring, side wings thereon engaging the ring and closing the groove, a pivotal connection between the wings and the sleeve, and a spring interposed between the sleeve 110 and the strip.
2. The combination with a shell having

an interior track provided with spaced contacts, the sides of the track being beveled to provide a reduced wear surface, of a shaft engaging sleeve, an outer ring for rolling contact with the track, an inner ring, said rings having ball races, balls within the races for holding the rings nested, one of the races having a lateral groove opening thereinto, a strip seated against the inner ring, wings thereon, one of the wings closing the groove to prevent displacement of

the balls, a pivotal connection between the wings and the sleeve, and a spring interposed between the strip and sleeve.

In testimony that I claim the foregoing as my own, I have hereto affixed my signature in the presence of two witnesses.

JESÚS M. LÓPEZ.
